UNITED STATES PATENT OFFICE

BARTHOLOMEW H. GREENE, OF SEBRING, OHIO

PRESS

Application filed August 20, 1928. Serial No. 300,699.

My invention relates more particularly to presses including a reciprocating head for forming clay products; and the objects of the present improvements are to provide a press which may operate more rapidly than the ordinary press used for such purposes, and to provide control mechanism for the press, including a brake which automatically stops the reciprocating head after the same has moved upwardly to a predetermined position.

These and ancillary objects are attained in the improved press of the present invention as will hereinafter be exemplified in detail, and claimed, and which may be stated in general terms as including means for operating the reciprocating head, reversible means for driving the operating means, a brake shoe movable into and out of braking engagement with the head operating means by the upward movement thereof, and means for simultaneously releasing the driving means from the head operating means.

A preferred embodiment of the improvement is illustrated in the accompanying drawing forming part hereof, in which—

Figure 1 is a front elevation of the improved press with portions broken away;

Fig. 2, a fragmentary side elevation thereof, as in the direction of the arrows 2—2, distant parts being removed;

Fig. 3, a fragmentary plan sectional view thereof, as on line 3—3, distant parts being removed.

Similar numerals refer to similar parts throughout the drawing.

The improved press, indicated generally at 10, may include a frame 11 upon which is mounted the bed 12. Spaced guide bars 13 and 13' extend upwardly from the bed 12, and a reciprocating head 14 is arranged for sliding movements up and down upon the guide bars, preferably by means of the upwardly extending screw 15, which screws in the tubular nut 16 mounted in a bridge bracket 17 supported at the upper ends of the guide bars 13 and 13'.

The lower end of the screw 15 is provided with a suitable connection with the reciprocating head 14, permitting rotation of the

screw and a raising and lowering of the head 14 by the screw as it is raised or lowered by reverse rotations thereof in the fixed nut 16.

The upper end of the screw is connected by a suitable coupling 18 with the lower end of a driven shaft 19, which passes through the hub 20 of a friction wheel 21, and which, as by means of a slot and key connection, is slidable therein and rotatable therewith.

The wheel 21 is mounted for rotation between a lower bearing 22 and an upper bearing 23 mounted in a bearing frame 24 supported upon the upper end of the press frame 11.

The friction wheel 21 is arranged to be alternately engaged by the outer peripheries of friction disks 25 and 26 located, respectively, at opposite sides of the shaft 19, and mounted, respectively, at the inner ends of coaxial shafts 27 and 28 which are slidably journaled respectively in bearings 29 and 29', and 30 and 30', carried by the bearing frame 24.

A pulley 31 is secured upon the shaft 27, and a pulley 32 is secured upon the shaft 28, and the respective pulleys are driven from the same power shaft (not shown), by means of belts 33 and 34 having the same direction of movement.

For axially reciprocating the shaft 27 to bring the disk 25 into and out of engagement with the wheel 21, a lever 35 is pivotally mounted as at 36 upon a bracket 37 extending outwardly from one side of the bearing frame, and the upper end 38 of the lever 35 is slidably and pivotally connected as at 39 with the outer end of the shaft 27, and the lower end 40 of the lever 35 is pivotally connected as at 41 with one end of a bar 42, which extends transversely of the main frame 11, preferably in front of the shaft 19.

The other end of the shaft 42 is pivotally connected as at 43 above the lower handle end 44 of an operating lever 45, which is pivotally mounted intermediate its ends as at 46 upon a bracket 47 extending outwardly from the side of the bearing frame opposite the bracket 37, and the upper end 48 of the lever 45 is provided with a slidable and pivotal connection as at 49 with the shaft 28, whereby movement of the operating handle 44 to the right,

as viewed on the drawing, will axially move the disk 26 into engagement with the wheel 21, and the disk 25 out of engagement with the wheel 21, and vice versa.

Preferably upon the upper bearing 23 for the shaft 19, brake levers 50 and 51 are pivotally mounted as at 52 and 53, respectively, on opposite sides of the bearing, and a brake shoe 54 is pivotally mounted, as at 55, upon one end 56 of the lever 50, whereby the brake shoe 54 may be lowered and raised by the lever 50 into and out of braking engagement with the top of the wheel 21.

Upon an end 57 of the lever 51, opposite to the end 56 of the lever 50, a brake shoe 58 is pivotally mounted as at 59, for lowering and raising into and out of braking engagement with the top of the wheel 21.

The other end 60 of the brake lever 50 extends beyond the periphery of the wheel 21, and similarly, opposite the end 60 of the lever 50, the other end 61 of the lever 51 extends beyond the periphery of the wheel 21, and the ends 60 and 61 are pivotally connected, respectively, as at 62 and 63, with the upper ends of downwardly extending brake rods 64 and 65, the lower ends of which are connected, respectively, with opposite ends of a transversely extending brake operating bar 66, which is preferably located above the coupling 18. The shaft 19 preferably extends through a central aperture 67 in the brake operating bar 66, whereby the lower face 68 of the bar 66 may be impinged by the upwardly moving coupling 18, elevating the bar 66 and thus lowering the brake shoes 54 and 58 into braking engagement with the wheel 21, for stopping the rotation of the same.

As illustrated, the disks 25 and 26 are in neutral position, and the belts 33 and 34 are being driven in the same direction indicated by the arrows thereon.

If the disk 25 is brought into frictional driving engagement with the wheel 21 by a movement to the left of the operating lever 45, the screw 15 will be rotated to lower the reciprocating head 14 for carrying out a pressing operation.

After the pressing operation has been completed, the operating lever 45 is moved to the right, and the disk 25 is disengaged and the disk 26 is engaged with the wheel 21, reversing the rotation of the wheel 21, and causing the screw 15 to reversely rotate to elevate the reciprocating head 14 until the coupling 18 strikes, as aforesaid, the brake operating bar 66, and causes the brake shoes 54 and 58 to engage with the wheel 21 and stop the rotation thereof.

For simultaneously disengaging the disk 26 from the wheel 21, during the braking of the wheel 21, a bell crank 69 is pivotally mounted as at 70 upon a suitable bracket 71 depending below the bearing frame 24, and one arm 72 of the bell crank laterally extends

above the brake operating bar 66, for being impinged by the upper face 73 thereof, and the other arm 74 of the bell crank extends downwardly across the bar 42 for impinging a collar 75 secured in a suitable position thereon.

Accordingly, when the brake operating bar 66 is raised, its upper face 73 will strike against the bell crank arm 72, swinging the same about its pivotal mounting, so that the other arm 74 of the bell crank will strike against the collar 75 and move the bar 42 to the left, thereby disengaging the disk 26 from the wheel 21.

I claim:

1. In a press and the like including a reciprocating head, means for operating the head including a rotatable wheel and a shaft keyed to the wheel and slidably axially of the wheel, the shaft being connected with the head for raising and lowering the head, means for driving the operating means, and means actuated by the shaft for disengaging the driving means when the head has reached a predetermined position.

2. In a press and the like including a reciprocating head, means for operating the head including a rotatable wheel and a shaft keyed to the wheel and slidably axially of the wheel, the shaft being connected with the head for raising and lowering the head, reversible means for driving the operating means, and means actuated by the shaft for disengaging the driving means when the head has reached a predetermined position.

3. In a press and the like including a reciprocating head, means for operating the head including a rotatable wheel and a shaft keyed to the wheel and slidably axially of the wheel, the shaft being connected with the head for raising and lowering the head, means for driving the operating means, a brake for the wheel, and means actuated by the shaft for moving the brake into braking engagement with the wheel when the head has reached a predetermined position.

4. In a press and the like including a reciprocating head, means for operating the head including a rotatable wheel and a shaft keyed to the wheel and slidably axially of the wheel, the shaft being connected with the head for raising and lowering the head, means for driving the operating means, a brake for the wheel, means actuated by the shaft for moving the brake into braking engagement with the wheel when the head has reached a predetermined position, and means actuated by the brake actuating means for disengaging the driving means from the head operating means simultaneously with the braking thereof.

In testimony that I claim the above, I have hereunto subscribed my name.

BARTHOLOMEW H. GREENE.
